SAUCE PAN OR THE LIKE

Robert R. Gibson, Reisterstown, Md., assignor to Corning Glass Works, Corning, N.Y., a corporation of New York

Filed Nov. 21, 1969, Ser. No. 20,224

Term of patent 14 years

Int. Cl. D7—02
U.S. Cl. D44—1

Fig. 1

Fig. 2

FIG. 1 is a top plan view of a sauce pan embodying my new design.

FIG. 2 is a front elevational view.

FIG. 3 is a side elevational view.

The characteristic feature of the design resides in the particular ornamentation applied to the outer wall, as shown.

I claim:

The ornamental design for a sauce pan or the like, as shown and described.
